MEDICAMENT DISPENSER

Barry H. Dash, 168 Woods Road, Englewood Cliffs, N.J.,
and William T. Eldridge, 65 Baywater Drive, Darien, Conn.

Filed July 19, 1963, Ser. No. 75,887

Term of patent 14 years

(Cl. D83—12)

FIG.4.

FIG.2.

FIG.3.

FIG. 1 is a side elevation of a medicament dispenser with the orifice cap in closed position; the opposite side is substantially the same in appearance.

FIG. 2 is a top plan view thereof;

FIG. 3 is a bottom plan view thereof; and

FIG. 4 is a side elevation thereof, with the orifice cap in open position.

We claim:

The ornamental design for a medicament dispenser, as shown and described.
